REEL MANDREL BUSHING LATCH FOR
BARBED WIRE MACHINES

Erick L. Ax and James A. Jackson, Pittsburgh, Pa.

Application April 8, 1949, Serial No. 86,237

5 Claims. (Cl. 308—24)

1

This invention relates to a latch and more particularly to a latch for holding a wire reel mandrel in the flyer of a barbed wire machine while barbed wire is being spooled thereon.

The take-up or spooling mechanism of a barbed wire machine serves two purposes; it not only winds the barbed wire onto a spool, but it also imparts a twist to the two wires making up the barbed wire strand as they are wound upon the receiving spool. The spooling and twisting mechanism of a conventional barbed wire machine consists essentially of a rotary flyer frame which houses a revolving reel-carrying unit and a traversing guide sheave. The reel-carrying unit is made up of a fixed revolving head mounted by means of a short shaft projecting therefrom to the inner side rail of the flyer frame and an axially retractable head removably mounted on the opposite rail of the flyer frame. A mandrel, for supporting the wire reel upon which the barbed wire is spooled, is mounted between the two heads with its ends resting in slots provided in the respective heads.

In order to remove a loaded reel of barbed wire from the reel-carrying unit, it is necessary to move the axially retractable head away from the end of the mandrel thus allowing the mandrel with its loaded reel of barbed wire to fall to the floor below the machine.

An object of our invention is to provide a latch which will hold the retractable head of the reel-carrying unit of a rotary flyer frame securely in position while barbed wire is being reeled thereon and which permits the head to be removed with ease so that the reeled barbed wire may be speedily unloaded.

This and other objects will be more apparent after referring to the following specification and attached drawings, in which:

Figure 1 is a plan view showing the invention installed on the rotary flyer frame of a barbed wire machine;

Figure 2 is an enlarged detail plan view partly in section;

Figure 3 is a front elevational view; and

Figure 4 is a sectional view taken on the line IV—IV of Figure 3.

Referring more specifically to the drawings, reference numeral 2 indicates a barbed wire machine rotary flyer frame casting, housing a revolving reel-carrying unit 4, and a traversing guide sheave 6. The flyer frame 2 is supported at one end by a hollow trunnion (not shown) and at its opposite end by a drive shaft 8. Drive shaft 8 is rigidly fixed to frame 2 and imparts rotary motion to the frame by a suitable belt and

2

pulley drive (not shown). Reel unit 4 is made to revolve within frame 2 by means of a bevel gear 10, fixed to a fixedly mounted revolving reel head 12, which meshes with bevel gear 14 fixed to a drive shaft 16. Shaft 16 is driven through suitable gearing by shaft 8. The reel carrying unit 4 is made up of the fixed revolving head 12, an axially retractable head 18 and a removable mandrel 20 which supports the wire reel upon which the barbed wire is spooled.

A latch plate 22 is pivotally mounted on the outer rail surface of the flyer casting 2. Retractable reel head 18 has rigidly affixed thereto a shaft portion 24 which is rotatively supported within flyer casting 2 by means of a bushing 26. Bushing 26 has a sliding fit within flyer casting 2. A shoulder segment 28 is formed by providing the outer end of bushing 26 with a reduced diameter portion 28. Reduced portion 28 projects beyond the flyer frame rail when the retractable reel head 18 is in normal closed position. A pull-out handle 30 is provided on the outer extremity of bushing 26. A circumferential groove 32 is provided in bushing 26 at a point approximately midway between its ends. Bushing 26 is held in position on shaft 24 by means of a washer 34 and a cap screw 36. Latch plate 22 is pivotally secured to flyer casting 2 by means of a cap screw 38. Latch plate 22 is drilled out at point 40 to receive a lock bolt 42 and a compression spring 44 which fits over the smaller diameter portion 46 of bolt 42. Lock bolt 42 is threaded as at 48 on one end to enable the affixing thereto of a handle 50 after bolt 42 and compression spring 44 have been inserted within hole 40. Although we have shown bolt 42 as being contained within latch plate 22 in hole 40, it will be noted that the bolt may be mounted on the surface of the latch plate if desired. The latch 22 is slotted out at points 52 and 54 for the reception of the reduced end portion 28 of bushing 26 within slot 52 and a projection, which we have shown as a cap screw 56, within slot 54 when head 18 is in the closed position as indicated by the solid lines in Figures 1 and 2. The cap screw 56 serves as a locking post inasmuch as lock bolt 42 holds the latch 22 in the closed position when released and allowed to slip into position behind cap screw 56 and across slot 54. When the latch plate 22 is in locked position slot 52 receives the reduced outer end of bushing 26 thus allowing the inner surface of the latch plate to bear against shoulder segment 28 to hold bushing 26 in closed position and thereby hold retractable head 18 in closed position.

In operation, to move reel head 18 to the open position, as shown in dotted lines in Figures 2 and 4, it is only necessary to move locking bolt 42 to the left by means of handle 50 and thus allow the pivotally mounted latch plate 22 to swing downwardly about the cap screw 38. The removal of latch plate 22 frees bushing 26 so that the operator can then withdraw it outwardly by means of handle 30 and thus withdraw head 18 from the mandrel 20 carrying the loaded barbed wire reel. When the latch plate 22 is swung to the open or downwardly projecting position, and bushing 26 is withdrawn to open position by means of handle 30, an arm segment 60, which is an integral part of the pivoted end of latch plate 22, will drop into the peripheral groove 32 of bushing 26 to lock it in open position and thus hold reel head 18 in the open or retracted position until an empty mandrel and wire reel are positioned between the reel heads.

After the mandrel and empty reel have been positioned within the flyer frame, reel head 18 is locked in the closed position by moving latch plate 22 upwardly or clockwise about cap screw 38, by means of a handle 62. This movement frees bushing 26 from the locking arm segment 60 and allows it to slide into closed position and thereby slide reel head 18 into closed operating position. Thus, when spring loaded lock bolt 42 snaps into position behind cap screw 56, the inner surface of latch plate 22, bearing against the shoulder segment 58 of bushing 26, will positively hold reel head 18 in the closed position.

While one embodiment of our invention has been shown and described, it will be apparent that other adaptations and modifications may be made without departing from the scope of the following claims.

We claim:

1. Mechanism for locking the reel-supporting bushing reciprocable in a hole through the side rail of a rotary flyer frame, said mechanism comprising a projection on the outer surface of said flyer frame rail adjacent said bushing, a reduced outer end on said bushing projecting beyond the flyer frame forming a shoulder, an elongated latch plate pivotally mounted on the outer surface of said flyer frame rail adjacent the bushing, said latch plate being adapted to be swung into closed position spanning said hole to hold said bushing therein, said latch plate having a slot adapted to receive said reduced end when said latch plate is in closed position, and manually operable locking means carried by said latch plate, said locking means being adapted to cooperate with said projection to lock said latch plate in closed position.

2. The improvement as defined by claim 1 characterized by said latch plate having a second slot adapted to receive said projection.

3. The improvement as defined by claim 1 characterized by said locking means comprising a spring loaded bolt slidably mounted on said latch plate, said spring loaded bolt being adapted to engage said projection when the latch plate is in closed position, and a handle carried by said bolt for retracting the same.

4. The improvement as defined in claim 1 characterized by said bushing having a circumferential groove around the surface thereof intermediate its ends, a handle projecting from said bushing for moving the same inwardly and outwardly from said hole, and said latch plate having a locking arm projecting upwardly from the pivoted end thereof, said locking arm cooperating with the circumferential groove in said bushing to lock the bushing in open position when the latch plate is swung into open position.

5. Mechanism for locking the reel-supporting bushing reciprocable in a hole through the side rail of a rotary flyer frame, said mechanism comprising a projection on the outer surface of said flyer frame rail adjacent said bushing, a reduced outer end on said bushing projecting beyond the flyer frame forming a shoulder, said bushing having a circumferential groove around the surface thereof intermediate its ends, a handle projecting upwardly from said bushing for moving the same inwardly and outwardly from said hole, an elongated latch plate pivotally mounted on the outer surface of said flyer frame rail adjacent the bushing, said latch plate being adapted to be swung into closed position spanning said hole to hold said bushing therein, said latch plate having slots along one edge thereof for receiving said projection and said reduced end when the latch plate is swung into closed position, manually operable locking means carried by said latch plate, said locking means comprising a spring loaded bolt slidably mounted on said latch plate, said spring loaded bolt being adapted to engage said projection when the latch plate is in closed position, a handle carried by said bolt for retracting the same, and a locking arm projecting upwardly from the pivoted end of said latch plate, said locking arm cooperating with the circumferential groove in said bushing to lock the bushing in open position when the latch plate is swung into open position.
